(57) **CLAIM**

I claim the ornamental design for a dispenser housing, as shown.

DESCRIPTION

FIG. 1 is an isometric view of a dispenser housing, showing my new design;

FIG. 2 is a front view thereof;

FIG. 3 is a right side view thereof;

FIG. 4 is a left side view thereof;

FIG. 5 is a top down view thereof; and,

FIG. 6 is a bottom view thereof.

Any broken line illustration of environmental structure in the figures is not part of the design sought to be patented.
